COOLING PLATE FOR MOLDING MACHINES

Aden A. English, Jersey City, and Albert A. Forster, Union, N. J., assignors to Standard Oil Development Company, a corporation of Delaware

Application July 13, 1935, Serial No. 31,202

1 Claim. (Cl. 257—256)

This invention relates to improvements in cooling plates for molding machines.

The invention will be fully understood from the following description taken in connection with the accompanying drawings, in which latter

Fig. 1 is a perspective view of a section of a molding machine showing cooling plates in perspective in their operative position in the molding machine. Fig. 2 is a longitudinally sectional view taken along the line II—II of Fig. 1. Fig. 3 is a transverse sectional view taken along the line III—III of Fig. 2.

Referring particularly to the drawings, reference numeral 1 designates the molding machine head. Channel carriers 3 extend from the head 1 toward an hydraulic ram (not shown). The molding machine is made up of alternate cooling plates 5 and mold sections 7 which are hung on the channel carriers 3 by means of flanges 8. The hydraulic ram (not shown) holds the cooling plates 5 and mold sections 7 together. The mold sections 7 and the cooling plates 5 cooperate to form a plurality of mold cavities 10. The mold cavities 10 are adapted to receive, while in melted condition, melted paraffin or other substances which are liquid when hot and which solidify on cooling.

Each cooling plate 5 is formed in halves 13 and 14 which are secured together by means of brass screws 16, or the like, to form a hollow body portion. The halves 13 and 14 are identical, except that they are made right and left hand in order to properly match. The screws 16 are preferably constructed of brass or other non-corrosive material. Each half section 13 and 14 of the cooling plate 5 is provided at opposite ends of its bottom wall 18 with semi-circular slots which, when the section halves are assembled, cooperate to form an inlet 19 and an outlet 20 for cooling liquid. Each section half 13 and 14 is provided with a vertically extending partition 22 which cooperates to form a channel 24 leading upwardly from the inlet 19. The partition 22 terminates at 25 in spaced relation to the top wall 26 of the hollow body portion. Each section half 13 and 14 is provided with flanges which cooperate when the section halves are assembled to form horizontally extending partitions 30 and 31. These partitions 30 and 31 extend horizontally from the partition 22 and terminate in spaced relation to the end wall 33 of the cooling plate. Each section half 13 and 14 is provided with flanges which, when the section halves are assembled, cooperate to form partitions 35 and 36 which extend horizontally from the end

wall 33 in spaced relation to partitions 30 and 31, and which terminate in spaced relation to the vertical partition 22. This results in the formation of a serpentine channel 40 which extends from the upper end of the channel 24 downwardly to the outlet 20. The section halves 13 and 14 are identical, as above described, except that they are made right and left hand to properly match. The joints between the section halves 13 and 14 are sealed with suitable sealing material, such as white lead or the like, designated 42. The section halves 13 and 14 are constructed of cast iron, or the like, and by means of the screws 16 and sealing material 42 a liquid-tight hollow body portion is formed.

Cooling fluid, such as salt water, is caused to flow through the inlet 19 of the assembled cooling plate. The cooling liquid flows upwardly through the channel 24 and into the channel 40 which conducts the liquid back and forth horizontally until it reaches the outlet opening 20. The cooling liquid is forced to the top of the cooling plate first where heat dissipation is greatest and then horizontally back and forth to the outlet 20 of the cooling plate. By this arrangement the cooling efficiency of the plate is increased a large amount, such as 15%, and the rate of flow of the cooling liquid at the upper turning point 25 where sediment has a tendency to collect is materially increased, thereby keeping the sediment in motion and causing the sediment to be ejected through the outlet 20. This construction of cooling plate permits of the use of salt water as a cooling medium. The baffle design is such that water flows continuously and keeps silt from settling out of the water and thereby eliminates stoppage of the channels 24 and 40 with silt.

The section halves 13 and 14 are preferably galvanized on their inner and outer surfaces, thereby eliminating the corrosion of the metal of the section halves. As a result, the channels 24 and 40 are provided with smooth surface walls which aid in keeping the silt in the cooling liquid in suspension or in motion. By constructing the cooling plate in section halves the plating or galvanizing of the inside walls of the section halves is facilitated. Furthermore, the section halves can be removed by simply unscrewing the screws 16 to permit cleaning of the cooling plate, if for some unusual reason the flow of cooling liquid through the channels 24 and 40 is stopped. The cooling plates and molding sections are adapted to mold cakes of any suitable size, for instance, melted wax can be solidified to form a commercial

cake 12" wide by 1½" thick by 19" long, and molded on end. The cooling plate sections constitute porous free and uniform castings since no cores are required in the preparation of the section halves. All of the surfaces of the section halves can be galvanized both outside and inside, thereby eliminating corrosion.

Various changes and alternate arrangements may be made within the scope of the appended claim, in which it is our invention to claim all novelty inherent in the art as broadly as the prior art permits.

We claim:

A device for molding solidifiable molten materials consisting of a frame having a rigid end member and side rails, a plurality of U-shaped mold sections supported by said side rails in spaced relation one to another, each of said sec-

tions having open sides and a centrally disposed vertical partition, a plurality of sectional hollow cooling plates of which one is disposed between each pair of mold sections co-operating therewith to provide a plurality of paired upwardly opening mold cavities, each section of said plates being formed with integral, inwardly faced, matching ribs providing a tortuous path for cooling liquid through each plate, said plates and mold sections being placed and maintained in operative association by pressure applied at the end of the assembly opposite said rigid end with the centrally disposed vertical partition of each mold section providing against distortion of the cooling plates under such pressure.
